UNITED STATES PATENT OFFICE.

GEORGE D. HARDER, OF COBLESKILL, NEW YORK.

BINDING ATTACHMENT FOR THRESHERS OR RUBBERS.

SPECIFICATION forming part of Letters Patent No. 604,319, dated May 17, 1898.

Application filed May 10, 1897. Serial No. 635,915. (No model.)

To all whom it may concern:

Be it known that I, GEORGE D. HARDER, a citizen of the United States, residing at Cobleskill, in the county of Schoharie and State 5 of New York, have invented certain new and useful Improvements in Binding Attachments for Threshers or Rubbers, of which the following is a specification, reference being had therein to the accompanying drawings.

10 My present invention relates to an improved binding attachment for threshing-machines, designed more especially for attachment to rye-threshers; and the object of the invention is to provide an improved form of 15 packer-arm which will operate effectively to gather in the light straw as it comes from the apron or straw-carrier and bind it into bundles prior to its final delivery from the machine.

20 I have illustrated the invention in the accompanying drawings, in which only a sufficient portion of the straw-carrier and the operating parts of the binder is shown to illustrate the invention and the operation thereof.

25 In the drawings, Figure 1 represents a perspective view of the binding attachment applied to the rear end of the straw-carrier of a 30 threshing-machine, a portion of the apron being broken away; and Fig. 2 is a detail view of one of the packer-arms.

Referring more particularly to the drawings, 3 represents the end of the straw-carrier of a threshing-machine of the ordinary or any desired form, and 4 the inclined binder-deck, 35 which, in connection with the guide-arms 5, forms a hopper or straw-box to receive the straw and supply it to the binding attachment at the bottom thereof. The driving or crank shaft which operates the packer-arms is 40 shown at 6, journaled in the frame-pieces 7 and carrying cranks 6^a, to which the packers 8 are pivotally connected by suitable connections 9, the lower ends of the packers being connected by suitable links with a stationary 45 part of the frame. These parts are located in rear of or beneath the inclined binder-deck, and the packers work through slots or elongated openings 4^a in the binder-deck, as shown in Fig. 1, being advanced through the slots 50 at the upper extremities thereof to grasp the straw and draw it downward and pack it into a compact bundle at the lower portion of the

box preparatory to the twine being wound around the bundle.

Owing to the extreme light and feathery 55 nature of the straw coming from a threshing machine it is very difficult to pack it into a bundle of sufficient size and weight to cause the tripper of the binder to loosen, and thus allow the needle to make its movement and the work of 60 making the finished bundle to be performed. This object I effectually overcome by forming the packer-arms in the manner shown in the drawings and more fully in detail in Fig. 2, in which it will be observed that the main or 65 body portion of the packer-arm terminates in a tooth 8^a and in rear of this tooth is provided with an angular extension 8^b. This angular extension or arm 8^b carries a number of teeth, preferably two, which are preferably 70 arranged concentric with each other, as shown at 8^c and 8^d. In the movement of the packer-arms the upper tooth catches a portion of the straw and draws it down to a position where the next tooth can take it in the next succeeding movement of the packer-arm. The 75 second tooth draws the straw still farther down into the path of the lower tooth, which on the next forward stroke of the packer will catch and press down into the bundle the 80 straw thus given it by the second tooth.

In order to prevent straw from dropping down behind the extension of the packer-arm after it has passed through the apron and thus being caught by the extension on its 85 backward movement, which would result in choking the packers and interfering with the working of the binder, a bow or curved arm 8^e is provided which forms a continuous curve from the upper tooth around to where its rear 90 end joins the body of the packer. The result of this is that while the packer is in its forward position the straw which is dropping down into the box or hopper rests upon the upper side of this bow and slides freely off 95 from the same on the backward movement of the packer.

Having thus described my invention, what I claim is—

1. In a binding attachment for threshers or 100 rubbers a packer comprising the body portion, the extension carried thereby having a plurality of teeth, and a curved guard extending from the extremity of said extension

to the main portion of the packer, substantially as described.

2. In a binder attachment for threshers or rubbers, a packer comprising the body portion, the extension carried thereby having a plurality of teeth, and the curved guard extending from the extremity of said extension to the body portion of the packer, said guard being formed integral with and being a curved

extension of the outermost tooth, substantially as described.

In testimony whereof I affix my signature in presence of two witnesses.

GEORGE D. HARDER.
